COOLING DEVICE

Albert G. Thomas, Lynchburg, Va.

Application October 8, 1936, Serial No. 104,614

3 Claims. (CL 62—126)

This invention relates to cooling devices such as those used in refrigerators and in air conditioning machines.

An object is to continually circulate a liquid refrigerant in a cooling chamber over the whole inner surface of the chamber until all of the liquid is vaporized.

An additional object is to regulate the temperature of the refrigerant entering the cooling element.

A further object is to remove the vapor from a cooling element without allowing the vapor to become superheated.

Other objects will appear in the following specification.

In the drawing:

Figure 1 is a side elevation, with end cover plate removed, of a cooling device in which the liquid refrigerant is re-circulated in the cooling enclosure.

Figure 2 is a front elevation, with front cover plate partly broken away, of the device shown in Figure 1.

Figure 3 is a front elevation, with cover partly broken away, of a cooling unit of folded construction and with means for re-circulating the refrigerant liquid.

Figure 4 is a plan view of the device shown in Figure 3.

Figure 5 is a cross sectional view of a double compartment conduit which can supply liquid refrigerant and remove vapor at the same time.

Figure 6 is a fragmentary elevation of a refrigerant temperature regulator.

In Figures 1 and 2 box 191 has narrow rectangular air slots 192 arranged so that air can pass through the slots from front to rear and thus to give up heat to thin metal walls 193, sealed to the front and rear slotted faces of the box so that the refrigerant therein cannot escape to the atmosphere.

Compressor pump 194, shown diagrammatically, draws refrigerant vapor through perforated hollow channels 203 placed between walls 193 thereby creating low pressure in box 191. These channels lead into manifold 204 passing through walls 193 and sealed to them to prevent leakage. Pipe 205 is connected with manifold 204 and leads the vapor to compressor 194. Pipe 205 is sealed to back 209 of box 191. A channel 203 is placed in box 191 between each adjacent wall 193 and a number of these channels at different levels may be employed to draw in vapor at many points.

Compressor 194 forces the refrigerant vapor into condenser 195, as usual, where it is liquefied.

The liquid is then forced through expansion valve 208 from which it passes to hollow channel 197 to which is fastened hollow plate-like channel 198 with one edge shown partly broken away to reveal holes 199 in the bottom, so placed that the refrigerant forced through these holes will be sprayed down on air passage walls 193. The refrigerant liquid will then flow down these walls by gravity, some of it absorbing sufficient heat from the metal to become vaporized. The excess liquid will fall into the bottom of box 191 and will be drawn into pipe 207 by pump 206 which will lift the liquid through pipe 202 to force it through manifold 201 and so through perforated pipes 200 so that the refrigerant liquid flows down again over walls 193 to absorb more heat from the air.

Pipes 207 and 202 are of course sealed to wall 209 to prevent leakage. Pump 206 could be placed in box 191 but it is shown outside so that the heat from the motor driving pump 206 can be more easily dissipated.

In operation, it will be seen then that the refrigerant vapor is drawn off where formed so that it does not become superheated by further contact with the metal cooling surfaces. Furthermore the liquid refrigerant in the box is circulated again and again over the metal cooling surfaces by pump 206 until it is vaporized so that all the heat transferred to the liquid is efficiently used. All of the heat extracted from the air assists in eventually vaporizing the refrigerant.

The amount of refrigerant admitted to box 191 through valve 208 may be regulated by any suitable system or valve 208 may be eliminated and channel 198 may be a simple pipe leading into box 191 at the bottom, with a float valve for maintaining a constant level of liquid refrigerant. Such valves are well known and require no description.

This cooling device is particularly efficient since the vapor is not superheated by coming into contact with the cooling surface and therefore the entire cooling surface may be employed entirely in evaporating the liquid refrigerant.

It is desirable to insulate pipe 205 from direct metallic contact with back 209 so heat will not be transferred between cooling surfaces 193 and pipe 205.

As shown in Figure 3, the cooling element 214 may be in the form of a thin metal conduit of rectangular cross section and folded back and forth to form a large surface area within a small space. While this form is shown the element may be coiled into a spiral or bent into any other de-

sired shape. Vertical channels 215, 216, and 217 are sealed to manifold 218, holes 219, 220 and 221 being provided to conduct refrigerant vapor from one to the other. These channels are also sealed to the back edges of the folds of element 214, holes 222 being provided so that refrigerant vapor can be drawn through them to channels 215, 216 and 217; thence to manifold 218 and from there to compressor 223 through pipe 224 sealed to 10 and connecting with manifold 218. Condenser 224a is provided and refrigerant liquid is forced through pipe 225 to expansion valve 226 and from there to the top edge of element 214 through pipe 210. The liquid then flows lengthwise down the 15 various folds which should be slightly inclined to assist the gravity flow. The element 214 may be inclined toward the rear also to prevent liquid from entering holes 222 which may also be placed above the normal liquid level. Any liquid that 20 reaches the end 227 of the bottom fold will be drawn through pipe 228 by pump 229 and forced up through pipe 230 into the topmost fold 214 again so that the liquid within the cooling element will be continually circulated until it is 25 vaporized and drawn off through holes 222.

The top part of conduit 214 is shown as partly broken away to reveal sinuous separator 231 which should be made of metal screening or of a perforated metal sheet. This separator is placed 30 between the upper and lower surfaces of conduit 214 and may be metallically bonded to them. It is for the double purpose of holding the surfaces apart when folded and to conduct heat from both metal surfaces to all parts of the liquid refrigerant flowing past. Outside fins may also be attached to element 214 and it may likewise have 35 corrugated surfaces to increase the area.

This type of cooling element is very economical to construct. It may be placed in various positions. For instance it may rest upon the folded edges and the liquid can be supplied through a folded perforated pipe in the top edge, the refrigerant flowing across the width of element 214 rather than lengthwise. Many other variations 40 are possible.

45 In Figure 5 is shown metal tube 231 with perfo-

rated partition 232 running lengthwise of the tube. The inner surface of tube 231 above partition 232 is coated with a heat insulating material 234 so that little heat from the metal will reach the vapor in space 235. Perforated partition 232 should also be covered with insulating material. Then the refrigerant 233 may be allowed to flow down tube 231, suitably inclined, and the vapor can be drawn off at all points through partition 232, without superheat.

5 As shown in Figure 6, pipe 275 supplying liquid refrigerant to cooling chamber 276 may be surrounded with pipe 277 through which the vapor is withdrawn from the cooling chamber. The liquid in pipe 275 is then heated by the vapor 15 in pipe 277 to approximately the correct temperature for any pressure in chamber 276. This arrangement may be used with the cooling devices shown in the drawing.

20 Since the refrigerant is brought to the vaporization temperature, or slightly lower, before it strikes the cooling surfaces, the device will operate efficiently.

25 Many changes of detail are possible without departing from the spirit of my invention.

What I claim is:

1. In a cooling device, a cooling element composed of a plurality of opposed surfaces, means for supplying liquid refrigerant to said surfaces, perforated conduits between said surfaces, and 30 means for withdrawing refrigerant vapor from said element through said conduits.

2. A cooling element in an evaporator for conducting refrigerant, said element comprising a conduit with a lower channel for conducting liquid refrigerant and an upper perforated channel 35 for exit of refrigerant vapor.

3. In a cooling device, a cooling element composed of a plurality of inclined surfaces, means for supplying liquid refrigerant to the upper portions of said surfaces, perforated conduits between said surfaces, and means for withdrawing refrigerant vapor from said element through said 40 conduits.
